UNITED STATES PATENT OFFICE.

HAROLD POTTER DONLE, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

DETECTOR.

Application filed April 6, 1922. Serial No. 550,307.

To all whom it may concern:

Be it known that I, HAROLD P. DONLE, a citizen of the United States of America, residing at Meriden, Connecticut, have invented new and useful Improvements in Detectors, of which the following is a specification.

This invention relates to devices for modifying the effects of received electro-magnetic waves to produce audible signal responses.

The primary object of my invention is to provide a sensitive, easily adjusted and dependable contact-type detector for radio signaling. By evacuating the chamber in which the active contact is located, I not only avoid the possibility of deleterious action upon the sensitive portions of the detector by moisture, dust or fumes in the atmosphere, but do away with oxidation which, in other contact detectors, after a few weeks or months materially reduces the sensitiveness, and which renders their action unreliable.

The invention contemplates the use of an evacuated tube containing two dissimilar electrodes which, together, constitute a sensitive couple, for the purpose of converting radio frequency currents such as are received in radio telegraphy or radio telephony. One of these electrodes is stationary with respect to the other, and the other is of a granular or divided material which has non-cohering characteristics, and which is so placed within the tube as to afford a variable or adjustable contact with the other or stationary contacts.

I have shown herein two adaptations of my invention, each of which has its merits for various purposes.

Figure 1 is a side view and partial longitudinal section of one form of device embodying the improvements of my invention;

Fig. 2 is a perspective view of the interior elements of the tube of Fig. 1;

Fig. 3 is a longitudinal sectional view showing another form of device embodying the principles of my invention.

The tube 4 may be of ordinary glass and is preferably evacuated sufficiently to minimize oxidation.

The sensitive couple in the form shown in Figs. 1 and 2 consists of metallic particles 5

and a socalled crystal or non-metallic substance 6. The particles 5 are preferably of substantial size and may be termed "grанules." They are also preferably of irregular or angular shape. The element 6 may be any one of the well known materials used in self-restoring contact detectors, such as commercial silicon, galena, iron pyrites, natural oxide of zinc, etc. These elements are mounted in the tube between the terminal plugs 7 and 8. The fixed or stationary active electrodes 6 may conveniently be spaced apart from the terminal 7 by means of a sleeve of glass or other insulating material 9.

For convenience in construction and assembling electrical connection between the electrode 6 and the terminal 8 may be formed or secured by means of a yielding conducting material, such as a loosely compressed or crushed mass of aluminum foil or tinfoil 10. The interior terminals 7 and 8 preferably substantially fit the interior of the tube and are connected by means of conductors 12 and 13 which extend through the sealed ends of the tube for external connections.

For convenience in handling and use I prefer to provide an exterior protecting shell 14, which may be made of transparent glass and have end caps 15 and 16 of metal, which are connected to the conductors 12 and 13, so as to form ready means of adapting the device to ordinary fuse clips as supports. The ends of the tube may be positioned in the shell and end caps by means of cement or other material 17.

For convenience in handling and adjusting the device a knob 18 may be provided at one end, preferably of insulating material.

It will be seen from the foregoing that, by reason of the construction and arrangement of the interior parts, it is possible to assemble the parts very readily within the tube 4, as none of the parts require to be cemented in place or soldered together. This type of assembling has an additional substantial advantage in that the absence of cement or other gas-absorbing or containing material within the tube 4 makes it possible to more readily and completely evacuate the tube and maintain a suitable non-oxidizing condition. It should be understood, however, that I do not consider the

invention in its broader aspects as limited to the particular construction described, except as required by the terms of the claims.

The device will ordinarily be mounted on a substantially horizontal axis, and the adjustment is effected by slowly rotating the tube on its axis until the particles fall into such position as to make the most sensitive contact with the electrode 6, as indicated by the greatest response in the associated telephone or other indicator.

In the form shown in Fig. 3 the terminal plugs 20 and 21 have their adjacent faces formed so as to provide the relatively stationary or fixed electrodes of metal, and the divided electrode 22 is formed of such crystalline or non-metallic, non-cohering material as galena, etc. The active faces of the members 20 and 21 are preferably inclined so as to provide a maximum facility of adjustment when the tube 23 and contents are rotated.

By mounting the sensitive, non-cohering couple in a vacuum I am able to use as the metallic element such highly conducting metals as silver, which are ordinarily considered unsuitable for non-cohering contact detectors on account of their rapid oxidation.

30 It should be understood that I contemplate that the detector herein described may be utilized in any suitable circuit, either with or without a battery.

I claim:

35 1. A detector comprising a tube, terminals mounted therein, a stationary electrode between said terminals, a yielding connection between said electrode and one of said terminals, a glass spacer between said electrode and the other terminal, and a finely divided electrode movable between said latter terminal and said stationary electrode.

2. A self-restoring detector comprising an evacuated tube, two terminals therein, a crystal, granular material between said crystal and one terminal and yielding material between said crystal and the other terminal.

3. A self-restoring detector comprising an evacuated tube, two terminals therein, a crystal conductively connected to one terminal, and granular material between said crystal and the other terminal.

4. A self-restoring detector comprising a tube, terminals therein, an electrode connected to one terminal, a spacing collar between said electrode and the other terminal and granular material between said electrode and the other terminal.

5. A detector comprising an evacuated tube, a terminal and a crystal therein, an insulating spacing collar between said terminal and said crystal and an electrode within said collar.

6. A detector comprising an evacuated tube, terminals therein, a crystal, a yield-

ing connection between one of said terminals and said crystal and granular electrode between said crystal and the other terminal.

7. A detector comprising a tube, terminals therein, an electrode, a compressible member between said electrode and one terminal, and a divided noncohering electrode between said first mentioned electrode and the other terminal.

8. A detector comprising an evacuated tube, a terminal, a crystal, and a granular metal electrode between said terminal and said crystal.

9. A detector comprising an evacuated tube, terminals therein, a non-metallic electrode, a granular metallic electrode between said non-metallic electrode and one terminal and a crushed foil member between said non-metallic member and the other terminal.

10. A detector comprising an evacuated tube, terminals therein, a crystal mounted between said terminals and electrically connected with one of said terminals, a spacing member between said crystal and the other terminal and a granular metallic electrode between said crystal and said other terminal.

11. A detector comprising a tube, terminals therein, an electrode, a compressible member between said electrode and one terminal, a spacing member between said electrode and the other terminal, and a divided non-cohering electrode between said electrode and said other terminal.

12. A detector comprising a tube, terminals mounted therein, a crystal mounted between said terminals, a crushed foil member electrically connecting said crystal with one of said terminals, a finely divided electrode movable between said crystal and the other terminal and a spacing member between said latter terminal and said crystal, for preventing said crystal from moving toward said terminal.

13. A detector comprising an evacuated tube, two electrodes therein comprising a sensitive couple, one of which is non-metallic and the other of which is composed of a series of angular metallic granules of substantial size.

14. A detector comprising a tube, a pair of terminals secured therein, and a sensitive couple mounted between said terminals and consisting of a crystal connected to one terminal and a series of angular metallic granules interposed between said crystal and the other terminal.

15. A detector comprising an evacuated vessel containing terminals sealed therein and electrodes electrically connected with said terminals within said vessel, one of said electrodes being of metal and the other of said electrodes forming in conjunction with the first mentioned electrode a non-microphonic, rectifying couple capable of operation

- without a direct current source, one of said electrodes being relatively massive and stationary and the other of said electrodes being relatively finely divided and movable with respect to the first mentioned electrode.
16. A detector comprising an evacuated vessel, terminals sealed therein, electrodes within said vessel electrically connected with said terminals, one of said electrodes being metallic and the other being non-metallic and forming in conjunction therewith a non-microphonic rectifying non-cohering couple capable of operation without a direct current source one of said electrodes being finely divided and movable with respect to the other and with respect to one of the terminals.
17. A detector comprising an evacuated tube, two contacts mounted therein constituting a rectifying couple, one of said contacts being of granular form, a housing for said tube comprising a shield and metallic end caps adapted to be rotatably supported to permit adjustment of the granular contact, conductors sealed in said tube and leading from said contacts to said end caps, and means for supporting said tube spaced apart from the inner walls of said shield.

HAROLD POTTER DONLE.
